CHARLES LE G. FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

SYSTEM OF DISTRIBUTION.

1,295,887.

Specification of Letters Patent.

Patented Mar. 4, 1919.

Application filed November 7, 1916. Serial No. 129,975.

To all whom it may concern:

Be it known that I, CHARLES LE G. FORTESCUE, a subject of the King of England, and a resident of Pittsburgh, in the county of Allegheny and State of Pennsylvania, have invented a new and useful Improvement in Systems of Distribution, of which the following is a specification.

My invention relates to electrical distributing systems and it has special relation to alternating-current distributing systems that are subjected to varying loads operating at variable power-factors.

More particularly, my invention relates to alternating-current railway systems which embody means for automatically maintaining fixed relations between the voltages impressed across the trolley conductors and the rails and across the return feeder-conductors and the rails, under all load conditions. At the same time, railway systems embodying my invention substantially minimize the resultant inductive effects that arise from the flow of the load currents therein. These inductive effects, unless suppressed, may impose disturbances upon circuits adjacent to the railway systems which will seriously interfere with the satisfactory operation of such adjacent circuits.

Many systems have heretofore been proposed for minimizing the inductive disturbances impressed upon one electrical circuit by another adjacent circuit but complete neutralization of these inductive effects has not been obtained in all cases. A particular system used in connection with electric railways, which has given fairly good results, embodies the use of series transformers to inductively interlink the trolley conductor and the track circuit. In consequence thereof, the return flow of the trolley currents is confined to the track rails or to portions of the earth closely adjacent to the track rails. In this manner, the zones of disturbing inducing influences that arise from the return flow of the power currents are restricted. Moreover, the returning currents are confined to limited regions close to the trolley conductor where their inductive effects on an adjacent intelligence-transmission circuit minimize or neutralize, to some extent, the disturbances occasioned by the

flow of the out-going trolley currents. This system is fully disclosed in U. S. Patent No. 1,196,300.

Another system in which the trolley conductor and the track circuit are interlinked and which is proposed for minimizing the inductive disturbances occasioned by the flow of power currents in an electric railway system, is disclosed in a co-pending application of A. W. Copley and Charles Le G. Fortescue, Serial No. 66,733, filed December 14, 1915 and assigned to the Westinghouse Electric and Manufacturing Company. This latter system comprises a feeder conductor, a trolley conductor and a track circuit. The first two conductors are so positioned with respect to an adjacent intelligence-transmission circuit, which is to be protected against inductive disturbances arising from the railway system, that the resultant electromotive forces induced therein by reason of the current flowing in the trolley and feeder conductors shall be neutralized to such a degree as will not seriously interfere with the operation of the intelligence-transmission circuit. Moreover, the trolley and feeder conductors are inductively interlinked, either with or without the track circuit, through transformers of a character similar to those employed in connection with the system disclosed in the above-mentioned patent.

An object of my present invention is to provide an improvement upon the aforementioned systems and particularly upon the system covered by application Serial No. 66,733, in which disturbances tending to arise from the flow of alternating currents in the distributing system may be substantially neutralized. In the system of the present invention, the voltages consumed by the inductive reactive-drops obtaining in the transformers which are connected between the trolley conductor and the return feeder are compensated for by supplying leading currents of proper values from an independent source to the system. In consequence thereof, the voltages obtaining between the trolley conductor and the track circuit and between the return feeder and the track circuit are maintained at a fixed ratio, usually a one-to-one ratio, under all load conditions.

induced in the telephone circuit will be substantially neutralized by inducing therein equal and oppositely-directed electromotive forces, under all conditions of load distribution on the railway system.

The telephone circuit 20 is assumed to be uniformly and equally spaced from the trolley conductor 1 and the return feeder 4. The track circuit 2, in this instance, is held at an electrical potential midway between the potential of the trolley conductor 1 and that of the feeder 4 by means of the transformers 11, 12, 11^a and 12^a, since the track circuit 2 is connected to conductors such as the conductor 14, which represent the common mid-points between the inducing and induced windings of the transformers. Accordingly, the ratio between the electromotive forces obtaining in the inducing and induced windings of each of these transformers is unity. The electromotive force induced in the winding 13 is, however, equal to the electromotive force impressed upon the winding 18 only under ideal conditions. The primary and secondary voltages of a transformer of this character are equal only when the reactive-drops in them are compensated for. Since the inductive reactive-drop in a transformer varies with varying loads it is essential to supply means for automatically compensating for the varying reactive-drops occasioned by different load conditions, in order that the electromotive forces obtaining in the windings 13 and 18 may bear a constant relation to each other which, in this particular case, is a one-to-one ratio.

In order to compensate for these inductive reactive-drops in the transformers, a synchronous condenser 21 is supplied. One terminal of this condenser is connected by means of a conductor 22 to a mid-tap 23 on the primary winding 9^a of the series transformer 8^a. The other terminal of the synchronous condenser is connected by means of a conductor 24 to the track section 3 by means of a bond 25. The power-factor of the current delivered to the system by the condenser 21 is varied automatically by means of a regulator of the vibrating-contact type. This, in turn, controls the exciting current supplied to a field winding 26 of the condenser 21. The condenser 21, in this instance, serves in the same manner as a power-factor-correcting device the functions of which are well known.

The regulator is of a form well known in the art and comprises an electromagnet 27 excited by a voltage transformer 28 and a second electromagnet 29 having two coils 30 and 31. The electromagnet 27 and the coil 31 of the electromagnet 29 are excited by means of the transformer 28, the secondary winding 32 of which is connected in circuit therewith. The winding 32 is influenced by two differentially wound primary windings

33 and 34, the former being connected between the trolley conductor 1 and the track circuit 2 and the latter being connected between the return feeder 4 and the track circuit 2.

The coil 30 of the electromagnet 29 is excited by means of a current transformer 35, the primary winding 36 of which is connected in series with the trolley conductor 1.

The vibrating-contact type regulator is, therefore, influenced by the currents obtaining on the railway circuit and also by the difference in the voltages obtaining between the trolley conductor and the track circuit and the return feeder and the track circuit. The regulator serves to vary the effective resistance of a resistor 37 connected in series circuit with a field winding 38 of an exciter 39. The exciter 39, in turn, supplies the exciting current to the synchronous condenser 21. By varying the effective resistance of the resistor 37, the current supplied to the field winding 26 of the condenser 21 is automatically controlled in order to compensate for the inductive reactive-drop obtaining in the transformers.

The form of regulator shown is well known in the art and further description of it is not deemed necessary. For a complete description however, of this type of regulator reference may be had to U. S. Patent No. 1,147,576.

To illustrate the electrical conditions obtaining in the railway system of Fig. 2 at a certain instant, assume that a locomotive 40 occupies a mid-position on the track section 3. The propulsion currents, which are represented by full-line arrows 41, flow through the winding 9 of the transformer 8 along the trolley conductor 1 and a trolley pole 42 to the locomotive 40. At this point, the propulsion currents divide into two equal portions that flow along the track circuit 2 in opposite directions. Since it is presumed that the track circuit 2 comprises uniform conductors and the train 40 occupies a mid-position thereupon, as mentioned above, one-half of the propulsion current flows through the impedance bond 16^a, a conductor 43, the primary winding 18^a of the transformer 12, a conductor 44 and the secondary winding 10 of the series transformer 8 to the return feeder 4.

The other half of the propulsion current flows along the track circuit 2, the impedance bond 16, the conductor 15 and the primary winding 18 of the transformer 11^a to the return feeder 4.

It will be apparent, therefore, that the propulsion currents flowing in the trolley conductor 1, intermediate the generator 5 and the points A—A of the system, is equal in value to, and opposite in direction from, that of the propulsion current flowing in the corresponding portion of the return feeder 130.

4. Therefore, the inductive effects arising from the flow of the propulsion currents over this portion of the railway system are neutralized if the reactive-drop obtaining in the transformer 12 is compensated for. 5. This inductive reactive-drop is compensated for because the condenser 21 furnishes sufficient leading current to the transformer system to overcome the inductive drop, 10 caused therein by the inductance of said transformer system. However, in order to efficiently obtain the desired compensation, it is necessary that the condenser 21 be connected to the transformers through the use 15 of balance coils for the purpose of preventing susceptibility to short circuit conditions, as will hereinafter be described in connection with Fig. 3.

It is necessary to neutralize the inductive effects arising from the flow of the currents in the portion of the railway system extending between the transformers 12 and 11^a. As mentioned above, one-half of the propulsion current flows through the winding 18^a of the transformer 12. An equally and oppositely directed current is, therefore, induced in the secondary winding 13^a of the transformer 12. The direction of flow of this induced current is represented 20 by the broken-line arrow 46. A locally closed circuit is, consequently, established in which flows an induced current that is equal to one-half of the propulsion current. This local circuit comprises the winding 13^a of the transformer 12, a section of the trolley conductor 1, the trolley pole 42, the train 25 40, a portion of the track circuit 2 and the impedance bond 16^a.

Similarly, one-half of the propulsion current flows through the winding 18 of the transformer 11^a. In consequence thereof, a current, the direction of flow of which is represented by the dot-and-dash arrows 47 and the value of which is equal to the second portion of the propulsion current, is induced in a local circuit which comprises the winding 13 of the transformer 11^a, a conductor 48, a portion of the trolley conductor 1, the primary winding 36 of the series 45 50 transformer 35, the trolley pole 42, the train 40, a section of the rail circuit 2, the impedance bond 16 and the conductors 14 and 15.

Since the induced current flowing through 55 the winding 13 is equal and opposite to the induced current flowing in the winding 13^a, the said currents simultaneously traversing the trolley conductor 1 neutralize their inductive effects impressed upon the telephone conductor 20. Again, the inductive effects arising from the propulsion current flowing along the trolley conductor 1 from the series transformer 8 to the trolley pole 42 are neutralized by the inductive effects 60 65 arising from the flow of the portion of the

propulsion current flowing along the section of the return feeder 4 that is intermediate the transformers 12 and 11^a.

Because, as previously assumed, the train 40 occupies a mid-position on the track section 3, the corresponding section of the trolley conductor 1 over which the entire propulsion current flows subtends a length of the telephone circuit 20 that is equal to one-half the length thereof subtended by the portion of the return feeder intermediate the transformers 12 and 11^a, over which flows one-half of the propulsion current.

If the inductive reactive-drops in the transformers were not compensated for in accordance with the varying loads obtaining in the system, the inductive effects severally arising from the currents traversing the trolley conductor and the return feeder would not be equal and opposite and, therefore, 80 will not completely neutralize each other. By automatically controlling the leading currents supplied to the system by the condenser 21, the inductive reactive-drops in the transformer windings may be completely compensated for and, therefore, the ratio 90 between the voltage impressed across the trolley conductor and the track circuit and the voltage impressed across the track circuit and the return feeder will be maintained constant. In this instance, the two aforesaid voltages are maintained equal and 95 in exact phase opposition to each other.

While the synchronous condenser 21 assists in completely neutralizing the inductive effects to which the telephone circuit 20 is subjected, it also serves to improve the power-factor of the system, thereby increasing 100 its operating efficiency.

In Fig. 3, the condenser 21 is connected 105 to adjacent transformers 11 and 12 through balance coils 49 and 50. Since the balance coils are similar in construction, I will describe only one of them in detail. The balance coil 49 comprises two windings 51 and 52 which are so disposed upon a magnetizable core member 53 as to simultaneously generate equal and oppositely directed magnetic fluxes. Corresponding terminals of the coils 51 and 52 are connected to a common conductor 54 that, in turn, is connected 110 to one terminal of the synchronous condenser 21. The other terminals of the coils 51 and 52 are severally connected, respectively, to those windings of the transformers 11 and 12 that are inserted between the trolley conductor 1 and the track circuit 2. In a similar manner, the balance coil 50 connects the other terminal of the condenser 21 to the transformer windings inserted between the return feeder 4 and the track circuit 2. In this manner, the condenser 21 may furnish 115 leading currents to the railway sections on both sides of the transformers 11 and 12.

The balance coils 49 and 50 are employed 120 125 130

when a synchronous condenser of a relatively low voltage is utilized for furnishing leading currents to a system that operates at a relatively high voltage. The field winding 26 of the synchronous condenser 21 is connected in circuit with an exciter, as shown in connection with Fig. 2. The exciting current supplied to the field winding 26 is also controlled by means of a vibrating contact-type regulator. The regulator and the attendant circuits are not shown in Fig. 3, since they may be identical with those shown in Fig. 2.

It will be observed that, by connecting the balance coils as shown in this figure, I have been able, not only to employ a low-potential synchronous condenser to compensate for the inductive drops in the high-potential transformer, but have also been able to so isolate the synchronous condenser that it is unaffected by short-circuit conditions existing in the aforementioned electric-railway system.

While I have shown and described, somewhat in detail, several embodiments of my invention, it will be understood by those skilled in the art that many modifications may be made therein without departing from the spirit and scope of the appended claims.

I claim as my invention:

1. An electrical railway circuit comprising a trolley conductor, a return feeder therefor, a track circuit, spaced transformers having their inducing and induced windings connected in series relationship between the trolley conductor and the feeder, whereby said railway circuit is sectionalized, means for connecting an intermediate point of said transformer windings to the track circuit, and means associated with said transformers for automatically compensating for the reactive-drops obtaining in them under different load conditions, whereby the voltages impressed upon the system by said inducing and induced windings will be maintained at a constant ratio, said means being so connected to the transformer that they are substantially free from disturbance by short-circuit conditions which occur in the system.

2. An electrical railway circuit comprising a trolley conductor, a return feeder therefor, a track circuit, spaced transformers having their inducing and induced windings connected in series relationship between the trolley conductor and the feeder whereby said railway circuit is sectionalized, means for interconnecting an intermediate point of said transformer windings to the track circuit, and means influenced by the load currents flowing in the system for automatically maintaining a constant ratio between the voltages impressed upon the system by the said inducing and induced windings, said means being connected to said transformers through balance coils.

3. An electrical railway circuit comprising

ing a trolley conductor, a return feeder therefor, a track circuit, spaced transformers having their windings connected in series between the trolley conductor and the feeder whereby said railway circuit is sectionalized, the inducing and induced windings of said transformers bearing a one-to-one voltage ratio to each other, and the inducing windings thereof being connected between the track circuit and the feeder and the induced windings being connected between the track circuit and the trolley conductor, and means for maintaining a fixed relation between the values of the voltages impressed upon the system by the said inducing and induced transformer windings, under all load conditions, said means being so connected to the transformer that they are substantially free from disturbance by short-circuit conditions which occur in the system.

4. An electrical railway circuit comprising a trolley conductor, a return feeder therefor, a track circuit, spaced transformers having their inducing and induced windings connected in series relationship between the trolley conductor and the feeder, means for interconnecting an intermediate point of said transformer windings to the track circuit, a synchronous condenser connected to the system, and balance coils connected between said condenser and the transformer system, the field excitation of said condenser being automatically controlled in accordance with the load conditions obtaining in the system whereby the inductive reactive-drops in said transformers may be compensated for.

5. An electric railway system comprising a trolley conductor, a return feeder therefor, a track circuit, a plurality of spaced series transformers for inductively interlinking the trolley conductor and the feeder, a transformer connected on each side of said series transformers for interconnecting said trolley conductor, said return feeder and said track circuit with one another, and means associated with some of said transformers that are connected in circuit on each side of said series transformers for automatically compensating for the reactive-drops obtaining in said transformers, in order that the values of the voltages obtaining between the track circuit and the trolley conductor shall maintain a fixed relation to the values of the voltages obtaining between the track circuit and the return feeder, under all load conditions.

6. An electric railway system comprising a trolley conductor, a return feeder therefor, a track circuit, a plurality of spaced series transformers for inductively interlinking the trolley conductor and the feeder, a transformer connected on each side of said series transformers for interconnecting said trolley conductor, said return feeder and said track circuit with one another, a synchronous con-

3
denser, balance coils connected in circuit therewith for connecting the synchronous condenser to both the inducing and induced windings of the transformers connected on both sides of said series transformers, and means for automatically varying the field

active-drop obtaining in the transformer windings connected thereto, under all load 10 conditions.

In testimony whereof, I have hereunto subscribed my name this 28th day of Oct. 1916.

CHARLES LE G. FORTESCUE.
